Specification for Design.

Patented Aug. 10, 1920.

Application filed April 19, 1920. Serial No. 375,174. Term of patent 14 years.

To all whom it may concern:

Be it known that I, OTTO L. MERTZ, a citizen of the United States, residing at Chicago, in the county of Cook and State of Illinois, have invented a new, original, and ornamental Design for Package-Ties, (C,) of which the following is a specification, reference being had to the accompanying drawing, forming a part thereof.

The figure is a perspective view of a package tie showing my design.

I claim:

The ornamental design for a package tie, as shown.

OTTO L. MERTZ.
